F. W. CHRISWELL,

RAILWAY CAR.

APPLICATION FILED MAR 29, 1921.

1,406,345.

Patented Feb. 14, 1922.

UNITED STATES PATENT OFFICE.

FREDERICK W. CHRISWELL, OF SEATTLE, WASHINGTON, ASSIGNOR TO PACIFIC CAR & FOUNDRY CO., OF SEATTLE, WASHINGTON, A CORPORATION OF WASHINGTON.

RAILWAY CAR.

1,406,345.

Specification of Letters Patent. Patented Feb. 14, 1922.

Application filed March 29, 1921. Serial No. 456,551.

To all whom it may concern:

Be it known that I, FREDERICK W. CHRISWELL, a citizen of the United States of America, and resident of the city of Seattle, in the county of King and State of Washington, have invented certain new and useful Improvements in Railway Cars, of which the following is a specification.

My invention relates to railroad cars and 10 consists of a car the purpose of which is first to carry heavy loads and second to have such strength in a transverse direction that it may be able to resist the side strains due to hauling heavy loads thereon. 15 and, further, one having such a construction of its floor and particularly of the outer edges of the floor, that it will be much easier to draw any heavy body thereon, as a piece of heavy machinery, than is possible 20 with cars of the usual construction. My invention further consists of a construction whereby a strong and simple form of stake may be provided which is readily attachable to and detachable from the car.

25 The features of my invention will be hereinafter described and the parts thereof which I believe to be novel and upon which I desire to secure a patent will be particularly defined by the claims terminating this 30 specification.

In the accompanying drawings I have shown and will now describe the type of construction which I now prefer to use.

Figure 1 is a side elevation of a half 35 length of a car built in accordance with my invention.

Figure 2 is an end view of the same car, one-half thereof being in section taken at a point towards the center of the car.

40 Figure 3 is a transverse section through one side edge of the car, showing the manner of securing the stake thereto.

The particular service for which the present car has been designed is the transportation from place to place of heavy logging engines which are mounted upon skids. It is, of course, obvious that it is as well adapted for the loading and handling of other heavy bodies of analogous character. I will, 45 however, describe it as employed in loading and transporting such logging engines, it being understood that any other use to which it is capable of being put is also contemplated.

50 The frame construction of the car to

which my invention has been applied is heavy, as it is designed for carrying very heavy loads. The present invention is, however, not concerned with the type of construction of the car frame except in such respects as are specifically pointed out. The car as here illustrated has two heavy side beams or sills 1, which are made of a built up construction. It is also provided with other longitudinal sills and these are bound together by suitable cross sills so placed and in such number as may be desired for making a car of the desired strength.

In the particular use mentioned for which this car was designed, the logging engines, 70 mounted upon skids which employ as their main supporting members two large and long logs, are loaded upon the car usually from the side and by means of blocks and tackle operated by the engine itself. As 75 these engines so mounted upon their skids are very heavy, often weighing ninety tons or more, this manner of loading is liable to bring a heavy lateral or side strain upon the frame of the car. With cars of ordinary 80 construction this has often sprung the entire car platform laterally, thus distorting it permanently.

Partly for the purpose of resisting such action I have provided this car with a floor 85 consisting of heavy metal plates 2. These plates are securely fixed to the car framing and preferably extend over the entire floor of the car. Such plates form a very rigid and strong stiffening web to resist any lateral distortion of the car body. At the same time they form a smooth and durable surface upon which to carry and to slide the engine and its skid or any other heavy object which may be handled upon the car. 90 95

In order to facilitate drawing the engine and its skid upon the car, the edges of the floor plates 2 are projected beyond the side edge of the frame and such projecting edge is turned down in a curve, as is shown at 20, 100 thus forming a rounded edge of a shape and size which will prevent digging into the bottom of the skids when loading the engines.

In the ordinary platform car the outer edges of the floor form a right angle. In 105 attempting to draw an engine mounted upon its skid upon a car of this sort, the sharp edge of the car floor is apt to dig into the bottom of the skid logs and thereby offer a serious resistance against movement of the 110

skid. This is particularly true if the engine and its skid prior to loading are supported upon a surface below the level of the car floor. However, with an edge rounded, as 5 is most clearly shown in Figures 2 and 3, a skid striking such an edge has a smooth rounded edge to slide over, thus very greatly reducing the resistance and also obviating any injury to the bottom surface of the skid.

10 The rounded edge of the floor plate is shown in the drawings as extending from one end of the car to the other. This rounded edge may also be carried over the ends of the car as shown at 21, if desired. This, 15 however, may in some cases be unnecessary. I contemplate so constructing it whenever this is desired.

I have shown filler blocks as interposed between the projecting edges of the floor and 20 the outer side surface of the sills, which materially strengthen and support such edges and prevent deformation. These consist of a series of blocks 3 in the form of castings which may be secured against the side surface 25 of the sills 1 and are shaped to conform to the under surface of the floor plate. I have also shown an angle bar, as 4, which is used to connect the floor plate to the sill, being located in the angle between the two. 30 Where such an angle bar is employed the filler plates will be recessed at the back to accommodate themselves to the outline of said angle bars. These angle bars are provided with bracket webs 30 which also materially stiffen them. As shown in Figure 35 1 these filler blocks do not extend entirely to the end of the car. This is, however, a matter of choice. The loading of a donkey engine upon the car will usually occur at the 40 center point of the length of the car. It will first be drawn upon the car and will then be turned so as to extend in the same direction as the car.

Such a car should be provided with means 45 for detachably securing stakes thereto which may be put in position after the donkey engine has been loaded and which will prevent side movement of the engine upon the car floor. For this purpose I provide a car 50 made in accordance with my invention with four stakes and means for securing them. To this end one of the filler blocks 3, located towards each end of each side of the car, is provided with a special web, as 31, upon 55 which is pivoted a stake-retaining link 5.

Associated with this is an arm 50 which extends downward and has its lower end turned somewhat outward as is clearly shown in Figures 2 and 3. This forms a seat or stop for the lower end of the stake. 60 The stake which it is contemplated will be used for this purpose is one which has a flat inner side surface, that is the side surface which is next to the car.

A convenient and efficient form of stake 65 is made from a short piece of railroad rail placed with its base inward. Such a stake 6 is shown in Figure 2 and by dotted lines in Figure 3. This has a lower end section 60 which is bent inwardly so that when the 70 stake is secured in position with the upper end vertical, this lower section 60 will bend inwardly so as to engage with the seat or stop 50.

The retaining link 5 is of such size as to 75 snugly receive the stake. When the stake is in position the link 5 will be horizontally placed, as is shown at the right hand side in Figure 2 and by dotted lines in Figure 3. When the stake is not in use the retaining link 5 will hang down as is shown at the 80 left side of Figure 2 and in full lines in Figure 3.

Cars of this construction have proved to be excellently adapted for the particular 85 purpose named. They are not deformed by the strains applied thereto while loading and they have the strength to safely carry the heavy loads applied even over rough tracks. They also facilitate loading so that 90 the time required for loading and unloading is very much reduced.

What I claim as my invention is:

1. A platform car having a body frame and metal floor plates secured to said frame 95 to form a horizontal stiffening web and at the edges of the car body curving downwardly to form rounded edges thereby facilitating drawing heavy loads thereon.

2. A platform car having a body frame 100 and heavy metal plates secured thereto to form a floor, said plates extending beyond the framing at the car sides and being rounded down to form a smooth rounded edge and filler blocks between said projecting edge and the outer sill of the frame. 105

Signed at Seattle, King County, Washington, this 7th day of March, 1921.

FREDERICK W. CHRISWELL.
